ATTORNEY

UNITED STATES PATENT OFFICE.

JOHN MORGAN HENDRIX, OF STATESBORO, GEORGIA.

COMMODE.

Application filed January 19, 1925. Serial No. 3,515.

To all whom it may concern:

Be it known that JOHN MORGAN HENDRIX, a citizen of the United States of America, residing at Statesboro, in the county of Bullock and State of Georgia, has invented new and useful Improvements in Commodes, of which the following is a specification.

It is a purpose of the present invention to provide, in a commode, a construction there-
10 of consisting of an open frame and includ-
ing means for raising and lowering a back
which is hingedly connected to the seat of
the commode. The seat is provided with a
substantial opening cooperating with an
15 arcuate recess or partial opening formed in
the back at a point adjacent the seat so that
the body of the user may comfortably en-
gage therewith, the back being capable,
through the medium of its adjusting means,
20 of assuming a position to support the back
of the user.

Another purpose is to provide a frame
with a shelf for the support of a pan for the
reception of the excrement.

25 It is to be understood that the particulars
herein given are in no way limitative and
that, while still keeping within the scope of
the invention, any desired modifications of
detail and desired proportions may be made
30 in the apparatus according to the circum-
stances.

The invention comprises further features
and combinations of parts to be hereinafter
set forth, shown in the drawings and
35 claimed.

In the drawings:

Figure 1 is a view in elevation of the im-
proved commode constructed in accordance
with the invention.

40 Figure 2 is a vertical longitudinal sec-
tional view showing the back raised through
the medium of its adjusting means.

Figure 3 is a vertical cross sectional view
of the commode, showing a shelf to support
45 a pan.

Referring to the drawings, 1 designates
the frame of the commode as a whole, which
comprises the uprights 2 at the four corners
50 thereof, and connecting the uprights (which
are angular in cross section) are continuous
braces 3. The braces may be constructed of
any suitable material, preferably sheet
metal, and secured to the upper longitudinal
55 braces, as at 4, are U-shaped straps 5 to
which a seat 6 is fastened by screws or the

like 7. Connecting an intermediate brace 3
at the end of the frame and adjacent end
uprights are angularly disposed braces 8.
Connecting longitudinal portions of the in-
termediate brace 3 and the uprights at the
60 foot of the frame are angularly disposed
braces 9. Secured to the longitudinal por-
tions of a lowermost brace 3 is a sheet metal
shelf 10 which may act as a support for
various articles.

Hingedly mounted on the seat, as at 11,
is a back 12. The adjacent hingedly con-
nected portions of the seat and back are
arcuately recessed or cut away, as at 13 and
14, providing an opening for the body of
70 the user. The arcuate recess 13 is of sub-
stantial size and properly curved to conform
to those portions of the body of the user be-
low the thighs, when the user is in sitting
posture. The arcuate recess or cut away por-
75 tion 14 is more shallow or of less depth than
the arcuate recess 13 and is of a shape to
conform to and be engaged by the back of
the user a short distance above the rump
thereof.

Secured to the longitudinal portions of an
intermediate brace 3 is a sheet metal shelf 15
for the support of a pan (not shown) which
is adapted to receive the excrement. The
seat and back are provided with a covering
16 of suitable fabric, such as rubber or the
like, there being a stuffing or padding be-
tween the covering and the seat and back.
The covering is in a continuous piece, though
the seat and back are hingedly connected.
This covering is fastened in any suitable
manner, as at 17, to the edges of the seat
and back. The covering also has an opening
corresponding and conforming to the open-
ing forming recesses of the seat and back.
In fact, the material forming the covering is
pulled through the opening of the seat and
back and is fastened, as at 18, to the under
surface of the back and seat.

The under face of the back is provided
with a pair of cleats 19 and 20 and pivotally
mounted, as at 21, to the longitudinal por-
tions of the lowermost brace 3 are the arms
22 of a forked member 23 which has a head
24. An adjusting screw 25 is operable
105 through the head to the end of which a
bevel gear 26 is swiveled, as at 27. The
screw 25 operates through the bevel gear and
has its upper end pivoted at 28 to the cleat
19 of the back. The pivotal connection 28
110

consists of the U-shaped bracket between the ears of which the screw is pivoted, the bracket being secured to the cleat.

The head of the forked member has a lateral bearing for a stub shaft 29 which is provided with a bevel gear 30 which meshes with the bevel gear 26. A crank 31 is carried by the stub shaft, and obviously by turning the crank in one direction, the screw 10 may be extended, thereby raising the back to any position as may be suitable to the patient or user of the commode, which is particularly applicable for use in operating rooms, as well as in other hospital wards. 15 By turning the crank in the opposite direction, the back may be lowered.

The invention having been set forth, what is claimed is:

20 A commode comprising a frame provided with transverse supports connecting the upper part of said frame and longitudinal supports connecting the lower part of said

frame, a seat secured to the transverse supports and resting on the frame, a back hinged to the seat, the adjacent hingedly connected parts of the seat and back having an opening conforming to the body of the user, a shelf on the frame immediately below the opening for the support of a pan, a padded covering of a continuous piece engaged over and secured at its margin to the seat and back, means consisting of a forked member pivotally supported on the said longitudinal supports at the lower part of the frame and having a head portion, a jack screw operatively pivoted to the back and passing through the head portion, and a device including intermeshing gears for rendering the jack screw extensible with regard to the forked member. 25 30 35 40

In testimony whereof he affixes his signature.

JOHN MORGAN HENDRIX.
